MIRROR MOUNTING AND SUPPORTING DEVICE

James W. Goss, Warren, Ohio

Application December 23, 1952, Serial No. 327,490

2 Claims. (Cl. 248—28)

The invention relates to means for mounting and supporting large unframed mirrors, or similar objects, upon a substantially flat wall or other surface, and more particularly to such a device incorporating adjustable, two-piece object supporting means, such as disclosed in my U. S. Patent No. 2,532,162, dated November 28, 1950.

The object supporting means of said patent comprises a plurality of similar two-piece devices, each comprising a double channel member for permanent attachment to a wall, and a hook member, slidably, adjustably attached to the channel member and being adapted for engagement with an edge portion of the mirror.

In mounting a rectangular mirror by means of said patented object supporting means, it is necessary to use at least four of the devices, each of which must be separately attached to the wall in proper position.

Where the mirror is mounted above a ledge, such as a mantel or fireplace shelf, two of the devices are located upon the wall so as to engage each side edge of the mirror, as shown in said Patent No. 2,532,162. However, where such a ledge is not available, two of the patented devices are positioned along the lower edge of the mirror, to support the weight thereof, and two more are positioned along the upper edge of the mirror to hold the same in vertical position, substantially against the wall.

This requires considerable accuracy in attaching the several separate object supporting devices to the wall at exactly the right points for engagement with opposite edges of the mirror, and also, in cases where the mirror is to be mounted upon uneven walls, this frequently requires straightening, fairing, blocking or other preparation of the wall.

It is an object of the present invention to provide means for mounting and supporting a mirror upon an uneven wall without the necessity of straightening, fairing, blocking or otherwise preparing the wall upon which the mirror is to be mounted.

Another object is to provide such a device including two metal strips for attachment to a wall in horizontal position, each strip having means for adjustably mounting two of said patented object supporting devices thereon.

A further object of the invention is to provide such a device in which each metal strip is provided with spaced, parallel rows of apertures for selectively receiving nails or screws at various points where solid anchorage, such as studding, may be encountered in the wall, and for also selectively receiving rivets or the like at various places for attaching the channel members of the object supporting devices.

A still further object is to provide spaced, parallel corrugations upon the back of each metal strip, to compensate for any uneven spots on the surface of the wall upon which the mirror is mounted.

The above objects together with others which will be apparent from the drawings and following description, or which may be later referred to, may be attained by constructing the improved mirror mounting and supporting device in the manner hereinafter described in detail, and illustrated in the accompanying drawings, in which:

Fig. 1 is a front elevation of one of the object supporting devices, showing the same detached from the metal strip;

Fig. 2 a detached, perspective view of the double channel member, forming a part of the object supporting device;

Fig. 3 a detached, perspective view of the adjustable, hooked member of the object supporting device;

Fig. 4 a detached, perspective view of the pad of felt, or the like, which is attached to the double channel member;

2

Fig. 5 a rear elevation of one end portion of the perforate, corrugated metal strip forming a part of the invention;

Fig. 6 a transverse, sectional view through the corrugated metal strip, taken as on the line 6—6, Fig. 5;

Fig. 7 a vertical, sectional view looking in the direction of the arrows 7—7, Fig. 10, through a mirror mounted upon a wall by means of the improved mirror mounting and supporting device, the central portion of the mirror and wall being broken out to reduce the size of the figure;

Fig. 8 a broken elevation showing the manner in which a ledge, such as a mantel or fireplace shelf, supports the lower edge of a mirror, with the object supporting devices attached to the ends of the horizontal metal strips for engaging the side edges of the mirror;

Fig. 9 an elevation of the two metal strips attached to the surface of a wall with the object supporting devices positioned thereon for engaging the upper and lower edges of a mirror; and,

Fig. 10 a front elevation of a mirror mounted by means of the devices shown in Fig. 9.

Referring now more particularly to the embodiment of the invention illustrated, in which similar numerals refer to similar parts throughout, the object supporting devices which form a part of the complete mirror mounting and supporting devices are shown in detail in Figs. 1 to 4.

These object supporting devices are of the general character disclosed in my Patent No. 2,532,162 above referred to. Each of these object supporting devices comprise generally the members 11 and 12, preferably formed of heavy sheet metal or the like. The member 11 comprises the relatively flat body 13 having overturned side margins 14 forming channels adapted to slidably receive the edge portions of the relatively flat body 15 of the member 12.

The flat body 13 of the member 11 is provided with spaced apertures 16 adapted to receive rivets, or the like, for attaching it to the perforate metal strips, as will be later described, and the flat body 15 of the member 12 is provided with an aperture 17, preferably in the form of an elongated slot, through which, in certain instances, one of the rivets may be located as will be later described.

Each of these object supporting devices comprises means for restricting free sliding action of the members 11 and 12 relative to each other, such means being shown in the drawings as comprising a spring finger 18 upon the member 12 adapted to be resiliently positioned in any one of the troughs of the corrugated surface 19 upon the flat body portion 13 of the member 11.

A hook 20 is formed upon the outer end of the member 12, adapted to engage around a marginal portion of a mirror, and, for the purpose of preventing damage to the mirror this hook may be lined with a resilient material, such as felt or the like, as indicated at 21.

Hereinafter the member 11 may sometimes be referred to as a double channel member and the member 12 as the hooked member. The mirror mounting and supporting device to which the invention pertains includes also a pair of perforate metal strips of a length somewhat less than the horizontal dimension of the mirror, these strips being indicated generally at 22.

Each of these strips is provided with two spaced, parallel rows of apertures 23, located near the upper and lower edges of the strip, for receiving nails, screws or the like, to be driven into studding or other solid anchorage in a wall.

The spacing of these apertures in each row is such that in any horizontal location of a strip upon a wall certain apertures 23 in each row will be so positioned that nails or screws may be driven therethrough into adjacent studs in the wall so as to solidly anchor the strips to the wall at spaced points.

The apertures 23 are also arranged so that in some cases, as will be later described, rivets located through the apertures 16 of the double channel member 11 may be passed through the apertures 23 of the strips in order to attach the double channel members to the strips.

For the purpose of stiffening the strips 22 which therefore can be made of light gauge strip metal, and for compensating for any unevenness in the surface of the wall

upon which the mirror is to be mounted, each strip 22 may be provided with spaced, parallel corrugations, or ribs, 24, located upon the rear side of the strip for contact with the wall, so that the space between these ribs, as well as the space above and below the ribs, may receive any projections or uneven spots upon the surface of the wall.

In using the mirror mounting and supporting device to which the invention pertains, to mount a mirror above a ledge such as indicated at 25 in Fig. 8, a double channel member 11 may be positioned horizontally at each end of each strip 22, being rigidly attached to the strip as by rivets 26, or the like, located through the apertures 16 in the member 11 and through apertures which may be provided for the purpose in the end portions of the strip 22. The spacing of the main body of the strip 22 forwardly of the rear surface of ribs 24 provides a recess in which the rear heads of rivets 26 may be located without touching the wall on which strip 22 may be mounted.

The two strips 22, each with a channel member 11 attached to each end thereof, as shown in Fig. 8, are located horizontally and secured to the wall W, by nails or screws 27 located through certain of the apertures 23 of the strips, and driven into studding or other suitable anchorage in the wall. These strips 22 are located in position upon the wall determined by an approximation of the desired position of the mirror.

The mirror 28 may then be set in place, with its lower edge resting upon the ledge or shelf 25, and the hooked members 12 inserted within the channel members 11 to a point where the hooks or fingers 20 thereof engage over the respective marginal portions of the mirror.

For the purpose of protecting the mirror, pads 29 of felt, or the like, may be attached to the outer surfaces of the channel members 11, for contact with the back of the mirror, while the resilient linings 21 of the hooks 20 engage the marginal edges of the mirror.

Once in proper position, the interengaging detent means 18-19 will hold the mirror against accidental shifting. The strips 22 are entirely hidden from view, and the object supporting means 11-12 are substantially hidden, when the mirror is thus mounted.

It will also be seen that the strips 22 and object supporting means 11-12, being interposed between the wall and the mirror, provide a slight space therebetween, which is desirable since it provides for air circulation between the mirror and wall, and prevents fogging of the mirror.

In cases where a ledge or shelf for supporting the mirror is not available, the mirror may be attached to, and supported upon the wall, as shown in Figs. 7, 9 and 10. For this purpose, a spaced pair of the object supporting devices 11-12, may be mounted in perpendicular position upon each of the metal strips 22, as best shown in Fig. 9, and attached thereto as by rivets 26, or the like. Here again the rear heads of rivets 26 are in the recesses at the rear of strips 22 provided by rearwardly impressed ribs 24 so as not to interfere with the wall on which the strips 22 are mounted.

In the event that the mirror is heavy, and it is feared that the holding action of the interengaging detent means 18-19 is insufficient to support the weight of the mirror, one rivet 26 may be passed through the opening 17 in the hooked member 12 and through the corresponding opening 16 in the channel member 11, and through an adjacent lower opening 23 in the lowermost strip 22.

The channel member 11 is also secured to the strip by another rivet 26 located through the other aperture 16 in the channel member and through an adjacent upper aperture 23 in the strip. This assembly prevents relative movement of the members 11, 12, and provides a firm ledge on which the lower margin of the mirror may be supported.

Two spaced channel members 11 are located in perpendicular position and attached to the uppermost strip 22 by rivets 25 located through the apertures 16 thereof, and through adjacent apertures 23 in the strip. The two strips 22 are then properly positioned upon the wall W, as shown in Fig. 9, and are firmly attached to the wall by nails or screws 27 driven through certain of the apertures 23 in the strips, and into studding or other suitable anchorage in the wall.

The lower edge of a mirror 28 may then be seated in the hooks 20 of the object supporting devices upon the lower strip 22, with the mirror tilted slightly forwardly,

after which the upper edge of the mirror may be swung backwardly until the hook members 12, upon the upper strip 22, can be pushed downwardly over the upper edge of the mirror, holding the mirror mounted upon the wall as shown in Fig. 10.

In the use of the mounting and support device of the invention the mirror may always be properly located in level position on a wall because level lines may be drawn on the wall, and one of the top or bottom edges of each strip 22 aligned with such line in nailing the strip 22 to the wall studding.

It will be apparent from the foregoing that a simple, efficient and effective device is provided for easily and securely mounting a mirror in desired position upon a wall or similar surface, without the necessity of straightening, fairing or blocking uneven portions of the wall surface, while at the same time providing a space between the mirror and the wall to permit circulation of air therebetween.

20 In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

30 Having now described the invention or discovery, the construction, the operation, and use of preferred embodiments thereof, and the advantageous new and useful results obtained thereby; the new and useful constructions, and reasonable mechanical equivalents thereof obvious to those skilled in the art, are set forth in the appended claims.

I claim:

1. A device for mounting and supporting an object such as a sheet glass mirror, said device comprising a 40 pair of substantially flat strips adapted to be fastened to a wall in spaced parallel horizontal position, spaced longitudinal ribs upon the rear face of each strip for contact with the wall, there being spaced parallel rows of apertures in each strip, means selectively inserted through 45 certain of said apertures for attaching the strips to a wall, object supporting devices secured to the fronts of said strips and having hooks for engaging over opposite edges of the mirror and holding the mirror spaced from said strips, the hooks of the object supporting devices upon 50 the lower strip projecting downwardly and opening upwardly, said upwardly opening hooks being fixedly mounted, the hooks of the object supporting devices on the upper strip projecting upwardly and opening downwardly, said downwardly opening hooks being mounted 55 for vertical adjustment.

2. A device for mounting and supporting an object such as a sheet glass mirror, said device comprising a pair of substantially flat strips adapted to be fastened to a wall in spaced parallel horizontal position, spaced longitudinal 60 ribs upon the rear face of each strip for contact with the wall, there being spaced parallel rows of apertures in each strip, means selectively inserted through certain of said apertures for attaching the strips to a wall, object supporting devices secured to the fronts of said strips and 65 having hooks for engaging over opposite edges of the mirror and holding the mirror spaced from said strips, means selectively inserted through certain other of said apertures for attaching said object supporting devices to said strips, the hooks of the object supporting devices upon 70 the lower strip projecting downwardly and opening upwardly, said upwardly opening hooks being fixedly mounted, the hooks of the object supporting devices on the upper strip projecting upwardly and opening downwardly, said downwardly opening hooks being mounted 75 for vertical adjustment.
